US00D839362S

(12) **United States Design Patent** (10) **Patent No.:** **US D839,362 S**
(45) **Date of Patent:** **** Jan. 29, 2019**

(54) **SPINNER**

(71) Applicant: **Prime Resources Corp.**, Bridgeport, CT (US)

(72) Inventor: **Jeffrey Lederer**, Greenwich, CT (US)

(73) Assignee: **BRODER BROS., CO.**, Trevose, PA (US)

(**) Term: **15 Years**

(21) Appl. No.: **29/619,953**

(22) Filed: **Oct. 3, 2017**

(51) LOC (11) Cl. **21-01**

(52) U.S. Cl.

USPC **D21/455**; D8/34

(57) **CLAIM**

The ornamental design for a spinner, as shown and described.

DESCRIPTION

FIG. 1 is a top perspective view of one embodiment of a spinner showing my new design;

FIG. 2 is a bottom perspective view thereof;

FIG. 3 is a top plan view thereof;

FIG. 4 is a front elevational view thereof;

FIG. 5 is a bottom plan view thereof;

FIG. 6 is a left side elevational view thereof;

FIG. 7 is a right side elevational view thereof;

FIG. 8 is a rear elevational view thereof;

FIG. 9 is a top perspective view showing an alternate embodiment of my new design for the spinner;

FIG. 10 is a bottom perspective view thereof;

FIG. 11 is a top plan view thereof;

FIG. 12 is a front elevational view thereof;

FIG. 13 is a bottom plan view thereof;

FIG. 14 is a left side elevational view thereof;

FIG. 15 is a right side elevational view thereof; and,

FIG. 16 is a rear elevational view thereof.

(Continued)

The broken lines in FIGS. 9 and 11 represent the feature that forms no part of the claim to the embodiment in which they are shown.

1 Claim, 4 Drawing Sheets
